(57) **CLAIM**

The ornamental design for a “food tray”, as shown and described.

DESCRIPTION

FIG. 1 is a rear view of one form of a food tray showing my new design;

FIG. 2 is a front view thereof;

FIG. 3 is a right side view thereof, the opposite side being identical thereto;

FIG. 4 is a top plan view thereof;

FIG. 5 is a bottom plan view thereof; and,

FIG. 6 is a top plan view of an alternate form of the food tray showing my new design, the rear, front and side thereof being identical to FIGS. 1-3.
